INVENTOR.

Joseph, Platt.

UNITED STATES PATENT OFFICE.

JOSEPH PLATT, OF DETROIT, MICHIGAN.

PASS TRAY.

Application filed April 22, 1926. Serial No. 103,820.

My invention relates to a pass tray and an object of my improvements is to provide a movable receptacle by which money or valuables may be transmitted through a bullet 5 proof partition without exposing an operator to an assault by a robber.

I accomplish this object in the apparatus illustrated in the accompanying drawings, in which:—

10 Figure 1 is an outside elevational view of an apparatus embodying my invention and parts adjacent thereto.

Figure 2 is a section of the same perpendicular to the partition.

15 Figure 3 is a section of the tray on the line 3, 3, Figure 2.

Figure 4 is a detail section showing the pivotal connection of the tray.

20 Figure 5 is a detail section on the lines 5, 5, Figure 2.

Figure 6 is a section similar to Figure 2, showing a modified construction of the cover.

25 Figure 7 is a perspective view of the cover of Figure 6.

Figure 8 is a perspective view of the stationary portion J of the cover of Figure 2.

Y is a counter, and K a partition of bullet 30 proof material. In the partition K, just above the counter Y and below a window is formed a rectangular opening of convenient size, generally extending for the breadth of the cashier's window.

35 Fitting in said opening is a tray X of the size and shape in cross section of the opening through the partition K. This is also made of bullet proof material and has a flat portion which is vertical in the normal position and forms a part of the partition K.

40 The tray X has two end plates and a bottom plate which is contiguous with the lower edge of said vertical portion, extends inward and bends upward slantingly terminating in an inner edge that is horizontal 45 and somewhat below the upper edge of said flat portion.

The tray X is pivoted to turn about an axis Z at its lower left hand corner and a stop V is provided to limit its inward motion of rotation.

50 J is a plate secured at its inner edge to the partition K and extending inward therefrom part way over the open end of the tray X. R is a cover extending from the 55 inner edge of said tray to and just beneath

the inner edge of the plate J. The cover R is movable and may slide in the ways indicated at the edges of the side plates of the tray X. Both the plate J and cover R should be of transparent bullet proof material.

The method of operating the above described device is as follows:

The cover R, being in the position shown in Figure 2 and the customer wishing to 65 pass an object to the cashier, the tray is rotated about the axis Z to bring it into the position shown in broken lines in Figure 2 and the customer may place the object in the tray, which is then turned backward 70 about the axis Z to the position shown in full lines in Figure 2. The cashier then moves the cover R upward so as to leave room for his hand to reach the object and remove it from the tray.

75 Instead of the movable plate R the plate J may be bent downward at its inner portion to extend into the interior of the tray X, as shown in Figure 6, so that a weapon cannot be used by a person outside of the 80 partition against a person inside of said partition.

What I claim is:

1. In an apparatus of the kind described, the combination of a bullet-proof partition 85 having an opening therethrough, a bullet-proof receptacle filling said opening open at the top and movable from one side of said partition to the other through said opening, means for constraining the motion of said 90 receptacle in said opening, said receptacle having sides one of which closes said opening at one limit of the travel of said receptacle and the other of said sides closes said opening at the other limit of the travel of 95 said receptacle, and a cover for said receptacle closing said opening during the intermediate travel of said receptacle.

2. In an apparatus of the kind described, the combination of a bullet-proof partition 100 having an opening therethrough, a bullet-proof receptacle filling said opening open at the top and movable from one side of said partition to the other through said opening, means for constraining the motion of said 105 receptacle in said opening, said receptacle having sides one of which closes said opening at one limit of the travel of said receptacle and the other of said sides closes said opening at the other limit of the travel of 110

said receptacle, and a transparent cover for said receptacle closing said opening during the intermediate travel of said receptacle.

3. In an apparatus of the kind described, 5 the combination of a bullet-proof partition having an opening therethrough, a bullet-proof receptacle filling said opening open at the top and movable from one side of said partition to the other through said opening, 10 means for constraining the motion of said receptacle in said opening, said receptacle having sides one of which closes said opening at one limit of the travel of said receptacle and the other of said sides closes said 15 opening at the other limit of the travel of said receptacle, and a cover movable from the inside of said partition for said receptacle closing said opening during the intermediate travel of said receptacle.
- 20 4. In an apparatus of the kind described, the combination of a bullet-proof partition having an opening therethrough, a bullet-proof receptacle filling said opening open at the top and movable from one side of said partition to the other through said opening, 25 means for constraining the motion of said receptacle in said opening, said receptacle having sides one of which closes said opening at one limit of the travel of said receptacle and the other of said sides closes said 30 opening at the other limit of the travel of said receptacle, and a cover secured to said partition and extending part way over said receptacle and a cover secured to said receptacle over the part of said receptacle left un- 35 covered by the first mentioned cover.
5. In an apparatus of the kind described, the combination of a bullet-proof partition having an opening therethrough, a bullet- 40 proof receptacle filling said opening open at the top and movable from one side of said partition to the other through said opening,

means for constraining the motion of said receptacle in said opening, said receptacle having sides one of which closes said opening 45 at one limit of the travel of said receptacle and the other of said sides closes said opening at the other limit of the travel of said receptacle, and a bullet-proof transparent cover secured to said partition and extending 50 part way over said receptacle and a cover secured to said receptacle over the part of said receptacle left uncovered by the first mentioned cover.

6. In an apparatus of the kind described, 55 the combination of a bullet-proof partition having an opening therethrough, a V-shaped bullet-proof receptacle open at the top and having its lower edge pivoted at the lower edge of said opening and being adapted to 60 turn about said pivot through said opening, and a cover extending over the upper end of said receptacle while it is turning through said opening.

7. In an apparatus of the kind described, 65 the combination of a bullet-proof partition having an opening therethrough, a V-shaped bullet-proof receptacle open at the top and having its lower edge pivoted at the lower edge of said opening and being adapted to 70 turn about said pivot through said opening, and a cover extending over the upper end of said receptacle while it is turning through said opening, said cover consisting of a part secured to said partition and extending part 75 way over said receptacle, and a part secured to said receptacle and extending over the part of said receptacle not covered by the first mentioned cover.

8. Claim 7 when either of said covers is 80 of transparent material.

In testimony whereof, I affix my signature.

JOSEPH PLATT.
